(57) **CLAIM**

The ornamental design for a protective face shield frame, as shown and described.

DESCRIPTION

FIG. 1 is a perspective view of a first embodiment of a protective face shield frame showing my new design;

FIG. 2 is a front elevational view thereof;

FIG. 3 is a rear elevational view thereof;

FIG. 4 is a side elevational view thereof, the opposite side being a mirror image;

FIG. 5 is a top plan view thereof;

FIG. 6 is a bottom plan view thereof;

FIG. 7 is a perspective view of a second embodiment thereof;

FIG. 8 is a front elevational view of FIG. 7;

FIG. 9 is a rear elevational view of FIG. 7;

FIG. 10 is a side elevational view of FIG. 7, the opposite side being a mirror image;

FIG. 11 is a top plan view of FIG. 7;

FIG. 12 is a bottom plan view of FIG. 7;

FIG. 13 is a perspective view of a third embodiment thereof;

FIG. 14 is a front elevational view of FIG. 13;

FIG. 15 is a rear elevational view of FIG. 13;

FIG. 16 is a side elevational view of FIG. 13, the opposite side being a mirror image;

FIG. 17 is a top plan view of FIG. 13; and,

FIG. 18 is a bottom plan view of FIG. 13.

The portions shown in broken lines are included for illustrative purposes only and form no part of the claimed design.
